UNITED STATES PATENT OFFICE.

JOHN GORGAS ROBINSON, OF PHILADELPHIA, PENNSYLVANIA.

DESIGN FOR A TOY BIRD.

Application filed April 15, 1922. Serial No. 1,769 Term of patent 3½ years.

To all whom it may concern:

Be it known that I, JOHN GORGAS ROBINSON, a citizen of the United States, residing at the city and county of Philadelphia, and State of Pennsylvania, have invented a new, original, and ornamental Design for a Toy Bird, of which the following is a specification, reference being had to the accompanying drawings, forming part thereof.

Figure 1 is a perspective view of a toy bird, showing my new design.

Figure 2 is a side view thereof.

Figure 3 is a top view thereof.

I claim:

The ornamental design for a toy bird, as shown.

In testimony whereof I affix my signature hereto.

JOHN GORGAS ROBINSON.
